UNITED STATES PATENT OFFICE

ERNEST C. STYBERG, OF RACINE, WISCONSIN, ASSIGNOR TO THE INSTANT FREEZER CORPORATION, OF RACINE, WISCONSIN, A CORPORATION OF WISCONSIN

APPARATUS FOR DISPENSING FRESHLY-REFRIGERATED FOODS

Application filed August 25, 1927. Serial No. 215,339.

My invention relates to the preparation and dispensing of ice-cream and other cooled or frozen edibles, and includes among its objects the provision of improvements in apparatus for preparing and handling such materials.

In the accompanying drawings,

Figure 1 is a side elevation of one illustrative type of device according to the invention;

Figure 2 is a transverse section on line 2-2 of Figure 1;

Figure 3 is a longitudinal section; and

Figure 4 is a fragmentary section similar to Figure 3, showing the parts in a different position of adjustment.

In the embodiment of the invention selected for illustration, the lower casing portion 10 has its bottom formed in the shape 20 of a relatively shallow tray sloping gently downward from both ends to the lowest point 12, which is somewhat nearer the rear end than the front end. Short legs 14 terminating in rubber feet 16 support the device with 25 the bottom 12 slightly spaced above the level of the supporting feet. An upper main cover 18 is detachably connected to the casing portion 10, as by reversely curved prongs 20 at the rear. The walls of the cover 18 are off- 30 set at 22 to form a shoulder for abutment with the upper edge of the casing 10 and support the weight of the cover. Upon rotation of the cover ninety degrees in a clockwise direction from the position of Figure

35 1, the prongs 20 may be withdrawn from the apertures at 24 in the casing. The cover may be fastened against removal by suitable means such as pivoted catches 21 entering receiving eyelets 23 mounted on the sides of 40 the casing 10. When the cover is thus fastened down, the handle 25 may be employed to pick up or manipulate the entire device.

The enclosure is completed by a lid 26 45 having prongs 28 at its upper and rearmost edge passing through openings in the cover 18 to provide a hinge connection, as clearly indicated in Figure 4. It will also be obvious that upon opening the lid somewhat 50 farther than the position of Figure 4, the

prongs 28 may be withdrawn and the lid detached from the cover 18.

Within the enclosure thus defined, I provide a hollow drum 30 for holding refrigerant. The drum illustrated is supported by 55 a small pindle 32 rotatably journaled at 34 in a bearing formed by semicircular openings in the edges of the casing 10 and cover 18; and at the other side by a much larger cylindrical flange 36 having similar supporting engagement with the edges of the casing 10 and cover 18, and surrounding the opening 37 for admitting refrigerant to the drum. The means illustrated for closing 60 said opening 37 comprises a ring 38 of wedge-shaped cross-section and of flexible material such as rubber, capable of forming a tight seal with the tapered inner wall of the flange 36. The ring is supported between opposing 65 cup-shaped discs 40 and 42 having their outer edges flared back to fit the wedge surfaces of the ring, and clamped together by suitable means such as the bolt 44 permanently riveted to the disc 40, and the wing nut 46 abutting the disc 42. The periphery 48 of the 70 drum is smooth, and the ends of the drum may be corrugated as at 50 to impart additional stiffness. For rotating the drum, I provide an integral lateral extension 52 extending radially from one side of the pindle 75 36 and carrying a suitable handle 54 at its outer end. The requisite stiffness for this arm may be obtained without the use of castings by turning down a stiffening flange 56 along the edge of the arm.

In front of the drum I mount a combined 80 scraper and charge holder, comprising a trough 58 closed at one end only, by an end wall 60. The edge of the metal at the other end is flared back as at 61 to form a smooth 85 lip for emptying out the contents. The trough is pivoted about an axis parallel to that of the drum and close in front of the drum, by means of hooks 62 at each end adapted to take over studs 64 projecting inwardly 90 from the sides of the casing 10. The wall next the drum is continued upwardly above the pivotal axis and curved outwardly as at 66. Upon reference to Figure 4, it will be evident that the operator can, by grasping the 100

finger piece 68, rotate the holder and scraper from the full line position to the dotted line position, in which it will engage the periphery of the drum and scrape off any film of frozen material with which the drum may be coated. When the receiver is not held in full line position by the operator, it falls back to the dotted line position of Figure 4, being prevented from further rotation in the clockwise direction by a stud 70 below the pivotal axis.

In use, the structure above specified is employed substantially as follows:

The entire device may be tipped over on its side by rotation ninety degrees in a clockwise direction from the position of Figure 2, and the stopper removed. A charge of refrigerant, such as cracked ice and salt, is packed into the drum and the stopper is replaced and gently tightened. The shrinkage of volume due to the melting of the ice will generate a substantial suction inside the drum, which will assist in maintaining the seal. The device is now returned to upright position, and upon lifting the lid 26 a charge of cold liquid to be frozen, such as milk or the various mixtures from which ice-creams and sherbets may be formed, can be poured into the front end of the tray.

Upon rotating the drum in a counter-clockwise direction, a film of material will be taken up by the periphery of the drum from this body of liquid, and the movement of the receiver to the dotted line position of Figure 4 will continuously remove the frozen film from the drum and direct it into the receiver.

After the appropriate amount has accumulated, the entire receiver may be easily lifted out of the device and the contents thereof transferred to a suitable serving dish or container. Alternatively, if it is desired to equalize or adjust the temperature of or mellow the material before serving, it may be transferred to a refrigerator, or it may be left in the receiver. In the full line position of Figure 4, the receiver is not in direct contact with the drum for heat transfer, but the air space surrounding the receiver will be rather effectively cooled by the drum. With the lid 26 entirely closed, one temperature condition will prevail in the casing, and with the lid propped open more or less, varying temperature conditions by reason of circulation of outside air may be obtained if desired.

The removal of the liquid material from the bottom of the tray may be continued until substantially all of the liquid has been transferred in frozen form to the receiver. This is because the clearance at 12 is very small, and because the contact of the casing 10 with the outer air will prevent the casing 10 from getting cold enough to permit any of the liquid in contact with the casing to become actually frozen.

After a portion of the liquid poured in has

been frozen, in case it is desired to change the contents, the entire device may be readily picked up and the contents of the tray poured back into any suitable receiver, or if the user prefers, the front feet 16 may be employed as a fulcrum, and the device may be tipped up on them and emptied without lifting its entire weight. The center of gravity of the entire device is approximately at the point 72 in Figure 1, and it will be noted that when the center of gravity is substantially vertically above the feet 16, the breast of the tray at 74 at the bottom of the top 76 will engage the supporting surface. Any danger of slipping of the device on an enameled counter or table is quite remote because when the weight is transferred to the breast at 74, the center of gravity of the device is almost vertically above the point of support.

After using, it is a simple matter to separate all the parts of the device and clean them. Everything except the rubber ring stopper 38, which is naturally laid aside before removing the charge from the drum, can be immersed in hot water or subjected to steam jets for quick cleaning and sterilizing.

Without further elaboration, the foregoing will so fully explain the gist of my invention, that others may, by applying current knowledge, readily modify and adapt the same for use under various conditions of service, without eliminating certain features which may properly be said to constitute the essential items of novelty involved, which items are intended to be defined and secured to me by the following claims.

What I claim is:

1. An instant freezer having a freezing cylinder, a cylindrical flange at one end having an inner surface defining a charging opening, and a plug for closing said opening, said plug comprising opposed discs having their outer edges flared back to define a wedge-shaped peripheral groove, a wedge-shaped annulus in said groove and means for drawing said discs together to expand said annulus against the inside surface of said opening.

2. A freezer having a freezing cylinder, a cylindrical flange at one end having a tapered inner surface defining a charging opening, and a plug for closing said opening, said plug comprising opposed discs having their outer edges flared back to define a wedge-shaped peripheral groove, a wedge-shaped rubber annulus in said groove and means for drawing said discs together to expand said annulus against the inside surface of said opening.

3. A freezer having a freezing cylinder, a cylindrical flange at one end having a tapered inner surface defining a charging opening, and a plug for closing said opening, said plug comprising a rubber annulus and means

for expanding said annulus against the inside surface of said opening.

4. An instant freezer comprising a main housing having its bottom formed into a tray for holding a liquid charge, a handle on top of said freezer behind the center of gravity, a lip at the front end of said tray over which the liquid in the tray can be poured out, supporting feet projecting from said tray, the front feet being positioned near said lip to remain in contact with a flat support during tipping of said freezer until said feet and lip are substantially under the center of gravity.

10 15 In testimony whereof, I have signed my name to this specification.

ERNEST C. STYBERG.
